BAG OPENING MECHANISM

George Long, Joliet, Ill., assignor, by mesne assignments, to Franklin Steel Works, Joliet, Ill., a corporation of Maine

Application September 8, 1936, Serial No. 99,776

18 Claims.

(Cl. 93—8)

The invention relates to bag handling mechanism and has particular reference to an improved bag feeding magazine having associated therewith novel bag opening means for successively removing a collapsed bag from the magazine and opening the same, whereby the open bag may be delivered to other mechanism having operation to fill the bag.

Automatic machines for filling and closing coffee bags generally include a magazine and means for opening the collapsed bags supported by the magazine. The improvements of the invention have been particularly adapted for use in connection with the bag filling and closing mechanism shown in the application of George Long and Elwell B. Larsen, Serial No. 87,972, filed June 29, 1936, although of course the utility of the invention is not limited to this or any special type of machine but on the other hand will find extensive application in many arts.

The primary object of the invention is to provide novel bag opening fingers and actuating means therefor which will produce vertical movement of the fingers for insertion within a collapsed bag and simultaneous horizontal movement and rotation to withdraw the bag from the magazine and open the same.

Another object of the invention is to provide bag opening fingers and means for actuating the same in a novel and improved manner which will impart bodily movement to the fingers in spaced horizontal and spaced vertical planes.

Another object of the invention is to provide bag opening means having improved operation for opening a collapsed bag, which will be of simple construction and economical to manufacture.

With these and other objects in view the invention may consist of certain novel features of construction and operation, as will be more fully described and particularly pointed out in the specification, drawings and claims appended hereto.

In the drawings which illustrate an embodiment of the invention and wherein like reference characters are used to designate like parts—

Figure 1 is an elevational view showing in associated relation the improved bag feeding magazine and bag opening means of the invention;

Figure 2 is a longitudinal sectional view of the magazine for supporting and feeding collapsed bags;

Figure 3 is a front elevational view of the bag magazine shown in Figure 2;

Figure 4 is a vertical sectional view taken sub-

stantially along line 4—4 of Figure 1 and showing the mechanism for actuating the fingers of the bag opening means;

Figure 5 is a horizontal sectional view taken immediately above the support for the bag opening fingers;

Figure 6 is an elevational view showing a collapsed bag and the position which the fingers assume when inserted within the same;

Figure 7 is an elevational view showing the bag of Figure 6 after the fingers have been rotated to open said bag; and

Figure 8 is a side elevational view of the open bag of Figure 7.

Referring to the drawings, particularly Figure 1, the supporting structure for supporting the apparatus of the invention consists of a plurality of uprights 10, 11 and 12 which rest on any suitable foundation such as 13. The central upright 11 extends considerably above the base structure of the machine as shown in Figure 4 and by means of horizontal brackets 14 supports the frame 15 of the bag opening mechanism to be more particularly described. A platform 16 extends under the frame to support the bags during opening thereof by the bag opening means, the same having integrally fixed thereto the hub 17 which is vertically movable on the upright 11. The links 18 pivotally connect the hub 17 and the movable blocks 20 supported on the foundation plate 21 and have threaded connection with the shaft 22 which can be rotated by the operator to thereby elevate or lower the platform and thus position the same at the desired height for the particular bags operated on by the machine. The bag feeding mechanism indicated in its entirety by numeral 23 is suitably supported on plate 24 to which is fixed the depending shaft 25. Said shaft provides a rack having meshing engagement with the pinion 26 journaled in bearing 27 suitably supported from upright 12. Rotation of the pinion is effected by handle 28 and thus the operator can elevate or lower the bag feeding mechanism to conform to the position of the platform 16.

The bag feeding mechanism shown in detail in Figures 2 and 3 comprises a pair of spaced side plates 30 which provide the arcuate base member 31 of the mechanism. Each side plate has suitably secured thereto the upstanding brackets 32 which act as supports for the side frames 33, the said supports retaining the frames in spaced relation and in supported position on base 31. As will be clear from Figure 2 the base 31 does not extend the full length of the frames 33, the said

opening or gap in the base being completed by an endless belt 34 passing over roller 35, journalled in the side plates 30 and located at the forward end of the mechanism and also passing over a 5 large driving roller 36 likewise journalled in the side plates 30 and located in substantial vertical alignment with the terminal end of the arcuate base 31. The collapsed paper bags indicated by numeral 37 are thus supported by base 31 10 and by the revolving belt 34, said belt having movement to propel the bags in a forward direction so that the forward bag can be readily removed by the bag opening means. A rolling block or other suitable weighted member 38 is located 15 to the rear of the collapsed paper bags and further propels the bags in a forward direction. Said block may be provided with a thrust plate 40 pivotally secured at 41 to the bar 42 and 20 yieldingly biased in a counter-clockwise direction by the coil spring 43.

The collapsed paper bags are retained at the forward end of the mechanism by a bottom clip 44, side clips 45 and a top clip 46 which engages 25 the top of the longest side of the bag, as will be clear from Figure 3, thereby enabling the bag opening fingers to pass between the collapsed sides of the bags. The clip 46 forms a part of the frame 47 suitably supported in position over the top of the bags by the bar 48, having connection 30 with block 49 which is fixed to the upright 12. The side guides 50, which engage and support the sides in the vicinity of the upper portion of the bags, are also supported by the frame 47.

35 The bag opening fingers 52, Figures 1 and 3, are eccentrically fixed to shafts 53 which are journalled by brackets 54 suitably secured to the horizontal reciprocating bars 55. These bars in addition to their horizontal movement have vertical movement which results in the bag opening fingers having a rectangular movement. The downward and upward strokes of this rectangular movement are utilized to thrust the fingers into the collapsed bag and to withdraw them from the bag opened thereby. The horizontal movement 40 produces rotation of the fingers so that they alternate from a flat position, which they assume when they enter the bag, as shown in Figure 6, to a parallel position as shown in Figure 7. The mechanism for producing this rectangular motion of the 45 bag opening fingers will now be described.

The actuating means essentially consists of three cams 56, 57 and 58, Figures 4 and 5, fixed to the cam shaft 60 suitably journalled by the spaced bracket 61 and which are integral with the frame 55 15. Said cams may be driven by a drive shaft 62 operatively connecting with the cam shaft 60 by means of gears 63. The cam 56 is provided with a cam race 64 within which is located a cam follower 65 fixed to arm 66. Said arm is journalled in bracket 61 at 67 and as shown in Figure 5 the rear of said arm is provided with gear teeth 68. Said teeth mesh with a pinion 70 fixed to shaft 71 journalled and extending between the brackets 60 61. Arms 72 are fixed to outer extending ends of said shaft and by means of links 73 the arms are 65 operatively connected to slides 74, respectively, which are located on each side of the frame 15 and suitably mounted with respect to the frame so as to have horizontal reciprocating motion. Secured to each slide 74 is a channel member 75, the same being vertically disposed and extending an equal 70 distance above and below the slide. The channel thereof receives the pin 76 secured by screw 77 to 75 its respective slide 55, the said slide carrying on its

outer end bracket 54, as previously described for supporting one of the bag opening fingers.

The slides are mounted for horizontal reciprocating movement in the member 78 which in turn is supported by the vertical guide member so as to have vertical reciprocating movement. The said guide 80 extends from end to end of the frame 15 and has flat sides connected by V-shaped surfaces, as clearly shown in Figure 5. Member 78 completely surrounds the guide 80 having opposed flat surfaces for engagement with the sides thereof of which are connected by portions having angular surfaces fitting the grooves of said member. As best shown in Figure 1, link 81 is pivotally connected to member 78 at 82, said link being pivoted at its upper end to lever 83 journalled for rotation in the frame 61 by shaft 84. Link 85 connects the rearwardly extending portion of the lever to an arm 86 which is supported for pivotal movement by shaft 71. The cam follower 87 rides within a cam race formed in the cam 57 and is fixed to the arm 86 which thus imparts motion to the linkage described to effect vertical reciprocation of the member 78 which thus carries with it the slides 55 and the bag opening fingers, as will be clear from the following description.

Each slide 54 carries bracket 55 which journals shaft 53 carrying one of the fingers. Each shaft 53 extends a short distance above bearing 54 and has suitably secured thereto a link 88, Figure 5. The outer end of each link, as at 89, is pivotally secured to an arcuate link 90 pivoted at 91 to the rigid arm 92 fixedly secured to and thus carried by the member 78. When the channel members 75 are reciprocated, motion is imparted to the slides 55 which bodily moves its respective bag opening finger from the full line position shown in Figure 5 to the dotted line position. However, the shaft thereof has operative connection through the links to a stationary member 92 and as a result of this relative movement rotation of each shaft 53 is effected, producing rotation of the bag opening fingers. When the parts are in full line position, Figure 5, the bag opening fingers are disposed in spaced parallel relation and when the parts are in dotted line position, the fingers are disposed with their flat sides in substantial alignment. In this latter position the fingers enter the bag and the member 78 is then forced downward into its lowermost position, causing the fingers to be inserted within and extend for the full length of the bag 93, see Figure 6. The slides 55 are then reciprocated in a direction rearwardly to effect removal of the bag from the feeding mechanism and as a result of this reciprocation the bag opening fingers will be rotated so that at the completion of said reciprocation the fingers will assume their spaced parallel position, Figure 7. This rotation of the fingers, which takes place on a vertical axis substantially coinciding with the outer edge of the respective finger, effects opening of the bag. The fingers are eventually withdrawn from the open bag by vertical upward movement of the member 78, whereupon the operations just described are repeated.

However, before the bag opening fingers are withdrawn from the bag a plunger 94 is inserted within the same in order to hold the bag against the platform 16 while upward movement of the fingers takes place. The plunger is suitably fixed to the end of rod 95 supported at its upper end by bracket 96 which extends outwardly of the member 97 suitably mounted on the guide member 80 for vertical reciprocating movement within the frame 15. The spaced arms of bracket 96

confine therebetween a coil spring 98 which engages at one end one arm of the bracket and at the other end a stop 99 fixed to the rod 95. The plunger is thus yieldingly caused to descend 5 within the open bag and is yieldingly forced into contact with the bottom thereof, although being positively returned to initial raised position.

Cam 58 is operatively connected to member 97 through link 100, lever 101, suitably journaled by shaft 84, link 102 and arm 103, journaled by shaft 71 and carrying a cam follower riding within a cam race provided by cam 58. Downward movement of the plunger occurs immediately after the bag has been opened by the fingers 52 15 and the same yieldingly holds the bottom of the bag against a base member 104, Figure 2, until the fingers are withdrawn. Said base member is supported by and forms part of the platform 16. Associated therewith are a pair of stationary 20 spring clips 105 and a pair of movable spring clips 106, the latter being carried by block 107 located below the base 104. Said block is mounted on pins 108 and thus reciprocates vertically, which motion is imparted thereto by the toggle 25 levers 109. Link 110 connects the toggle levers with lever 111 pivoted at 112 to block 49 fixedly secured to the upright 12. The upper end of lever 111 is connected by a relatively long link 113 to one of the arms 72 as will be clear from 30 an inspection of Figure 1. Movement of this arm will rock lever 111 and break the toggle formed by the toggle levers 109 with the result that the spring clips 106 will be lowered substantially flush with the base 104. Return of the 35 lever 72 to its initial position, as shown in Figure 1, will locate the toggle levers in a straight line position, whereupon the spring clips will be elevated to their highest position. This action of the spring clips takes place in timed relation 40 with the removal and opening of the bag and the clips will be elevated so as to engage the bottom of an open bag as the plunger 94 forces said bottom of the bag into contact with the base member 104. The movable clips, together with 45 the stationary clips, will retain the bag in position on the base until the plunger is withdrawn.

The endless belt 34, previously described as having movement to propel the bags in a forward direction so that the forward bag can be 50 readily removed by the bag opening fingers, receives actuation from lever 111 through link 114 which is pivotally connected to the upper end of lever 115 suitably fixed to shaft 116 supporting the driving roller 36. The pawl 117, carried by 55 lever 115, is adapted to engage the ratchet 118 also fixed to shaft 116 and as the lever 115 is rocked the ratchet will be advanced one notch in a clockwise direction. The pawl 120 prevents reverse rotation of the driving roller.

60 A quantity of collapsed bags will be held by the bag feeding mechanism of the invention in compact relation and as the endless belt 34 is given intermittent movement, the bags will be propelled forward of the mechanism, thus maintaining the forward bag firmly against the clips 45 and 46. The bodily movement of the fingers 52 may be described as rectangular since they have downward movement for inserting the fingers when in a flat aligned position within the collapsed bag and are then given bodily movement in a horizontal and rearward direction to 65 remove the bag from the mechanism and simultaneously open the bag since this bodily movement effects rotation of the fingers whereby at

the end of said movement they assume a spaced parallel position. The movement of the plunger downwardly until the same engages the bottom of the open bag, which is accomplished by cam 58, serves to hold the bag firmly against the base 5 104 while the fingers are withdrawn. It is noted that this downward movement of the plunger is produced through the coil spring 98, providing safety means in the event some obstruction should prevent downward movement of the 15 plunger. It will be observed that rotation of the bag opening fingers takes place on a vertical axis which substantially coincides with the rear edge of the respective fingers. This construction has proven very satisfactory in quickly and efficiently 20 opening collapsed paper bags such as coffee bags and the construction has the additional advantage in that a filling spout may be substituted for the plunger so as to fill the bags immediately upon opening of the same by the fingers. It will 25 be evident from Figure 5 that the parts effecting rotation of the fingers have ample clearance with respect to the plunger which is axially located and positioned directly over the opened bag.

The invention is not to be limited to or by 25 details of construction of the particular embodiment thereof illustrated by the drawings, as various other forms of the device will of course be apparent to those skilled in the art without departing from the spirit of the invention or the 30 scope of the claims.

What is claimed is:

1. Bag opening means comprising a pair of bag opening fingers, each finger being substantially flat throughout its entire length, and means 35 rotating said fingers from a position wherein the fingers are disposed edge to edge with their corresponding faces in alignment to a position substantially 90 degrees removed therefrom whereby the faces which were in alignment are 40 disposed in approximately parallel planes.

2. Bag opening means comprising a pair of bag opening fingers, each finger being substantially flat throughout its entire length, and means 45 rotating said fingers from a position wherein the fingers are disposed edge to edge with their corresponding faces in alignment to a position 90 degrees removed therefrom whereby the faces which were in alignment are disposed in approximately parallel planes, the pivot 50 axis of each finger substantially coinciding with the outside edge of the finger.

3. Bag opening means comprising a pair of bag opening fingers, each finger being substantially flat throughout its length and having a 55 width less than one-half the width of the bag, and means rotating said fingers from a position wherein the fingers are disposed edge to edge with their corresponding faces in alignment to a position 90 degrees removed therefrom whereby the faces which were in alignment are disposed in approximately parallel planes, the pivot axis of each finger being vertical and substantially coinciding with the outside edge of the finger.

4. Bag opening means comprising a pair of bag opening fingers, each finger being substantially flat throughout its length, means supporting said fingers for rotation on a vertical axis and for bodily movement, and means producing rotation of said fingers from a position wherein 65 the fingers are disposed edge to edge with their corresponding faces in alignment to a position 90 degrees removed therefrom whereby the faces which were in alignment are disposed in approximately parallel planes.

5. Bag opening means comprising a pair of bag opening fingers, each finger being substantially flat throughout its length, means supporting said fingers for rotation on a vertical axis and for bodily movement, and means producing rotation of said fingers from a position wherein the fingers are disposed edge to edge with their corresponding faces in alignment to a position 90 degrees removed therefrom whereby the faces 5 which were in alignment are disposed in approximately parallel planes, the pivot axis of each finger substantially coinciding with the outside edge of the finger.
10. Bag opening means comprising a pair of bag opening fingers, each finger being substantially flat throughout its length, means supporting said fingers for rotation on a vertical axis and for bodily movement, said bodily movement comprising movement in a horizontal plane and movement in a vertical plane, and means producing rotation of said fingers as a result of their bodily movement in a horizontal plane.
15. Bag opening means comprising a pair of bag opening fingers, each finger being substantially flat throughout its length, means supporting said fingers for rotation on a vertical axis and for bodily movement, said bodily movement comprising movement in a horizontal plane and movement in a vertical plane, and means producing rotation of said fingers as a result of their bodily movement in a horizontal plane.
20. Bag opening means comprising a pair of bag opening fingers, each finger being substantially flat throughout its length, means supporting said fingers for rotation on a vertical axis and for bodily movement, said bodily movement including vertical reciprocating and horizontal translating movement, and means producing rotation of said fingers as a result of their horizontal translating movement, the pivot axis of each finger substantially coinciding with the outside edge of the finger.
25. Bag opening means comprising a pair of bag opening fingers, each finger being substantially flat throughout its length, means supporting said fingers for rotation on a vertical axis and for bodily movement, said bodily movement including motion in spaced vertical planes and 30 in spaced horizontal planes, and means producing rotation of said fingers as a result of their motion in each of the spaced horizontal planes.
30. Bag opening means comprising a pair of bag opening fingers, each finger being substantially flat throughout its length, means supporting said fingers for rotation on a vertical axis and for bodily movement, said bodily movement including motion in spaced vertical planes and 35 in spaced horizontal planes, and means producing rotation of said fingers as a result of their motion in each of the spaced horizontal planes.
35. Bag opening means comprising a pair of bag opening fingers, each finger being substantially flat throughout its length, means supporting said fingers for rotation on a vertical axis and for bodily movement, means producing rotation of said fingers as a result of their bodily movement to cause said fingers to pivot from a 40 position with their corresponding faces in alignment to a position substantially 90 degrees removed therefrom, whereby said fingers cause opening of a collapsed bag thereon, and a vertical reciprocating plunger having downward movement to enter the bag after opening thereof.
40. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 45 a result of said movement in the spaced horizontal planes.
45. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 50 a result of said movement in the spaced horizontal planes.
50. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 55 a result of said movement in the spaced horizontal planes.
55. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 60 a result of said movement in the spaced horizontal planes.
60. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 65 a result of said movement in the spaced horizontal planes.
65. Bag opening means comprising a pair of bag opening fingers, each finger being substantially flat throughout its length, means supporting said fingers for rotation on a vertical axis, means imparting bodily movement to said supporting means, including movement in a vertical plane and movement in spaced horizontal planes, and means producing rotation of said fingers as 70 a result of said movement in the spaced horizontal planes.
70. Bag opening means comprising a pair of bag opening fingers, each finger being substantially flat throughout its length, means supporting said fingers for rotation on a vertical axis, means imparting bodily movement to said supporting means whereby said fingers have downward movement in a vertical plane to insert said fingers within a collapsed bag, and movement 75 rearwardly in a horizontal plane, means produc-
- ing rotation of said fingers as a result of said rearward movement, whereby the fingers pivot from a position with their flat surfaces in alignment to a position 90 degrees removed therefrom, which pivotal movement causes opening of the collapsed bag thereon, and a vertical reciprocating plunger having downward movement to enter the bag after opening thereof.
75. Bag opening means comprising a pair of bag opening fingers, supporting means for said fingers including bars mounted for horizontal reciprocating movement and which rotatably support the fingers permitting rotation on a vertical axis, a member mounted for vertical reciprocating movement, said member carrying 80 said bars whereby the bag opening fingers have vertical movement in spaced planes and horizontal movement in spaced planes, and means producing rotation of said fingers as a result of their bodily movement in the horizontal planes.
80. Mechanism for opening collapsed bags including a pair of bag opening fingers, supporting means for said fingers including bars mounted for horizontal reciprocating movement and which rotatably support the fingers permitting rotation 85 on a vertical axis, a member mounted for vertical reciprocating movement, said member carrying said bars, means producing horizontal reciprocating movement of said bars, other means vertically reciprocating said member whereby said bag opening fingers have vertical movement in spaced planes and horizontal movement in spaced planes, and means producing rotation of said fingers as a result of their bodily movement in the horizontal planes.
85. Mechanism for opening collapsed bags including a pair of bag opening fingers, supporting means for said fingers including bars mounted for horizontal reciprocating movement and which rotatably support the fingers permitting rotation 90 on a vertical axis, a member mounted for vertical reciprocating movement, said member carrying said bars, means producing horizontal reciprocating movement of said bars, other means vertically reciprocating said member whereby said bag opening fingers have vertical movement in spaced planes and horizontal movement in spaced planes, and means producing rotation of said fingers as a result of their bodily movement in the horizontal planes.
90. Mechanism for opening collapsed bags comprising a pair of bag opening fingers, supporting means for said fingers including bars mounted for horizontal reciprocating movement and which rotatably support the fingers permitting rotation 95 on a vertical axis, a member carrying said bars, means mounting said member for vertical reciprocating movement, cam means operatively connecting with said member and producing vertical reciprocation thereof, other cam means for producing horizontal reciprocating movement of said bars, whereby said bag opening fingers have vertical movement in spaced planes and horizontal movement in spaced planes, and links constructed and arranged to cause rotation of said fingers as a result of their bodily movement in the horizontal planes.
95. Mechanism for opening collapsed bags comprising a pair of bag opening fingers, supporting means for said fingers including bars mounted for horizontal reciprocating movement, a shaft projecting upwardly from each of said fingers and being rotatably mounted by one of said bars, whereby said fingers are rotatable on a vertical axis, a member carrying said bars and mounted for vertical reciprocating movement, means producing vertical reciprocation of said member, other means for causing horizontal reciprocating movement of said bars in unison, whereby said bag opening fingers have vertical movement in spaced planes and horizontal movement in spaced planes, and links pivotally connecting the shaft of each finger to said member and constructed and arranged to produce rotation of said fingers as a result of their bodily movement in a horizontal plane.
100. Mechanism for opening collapsed bags comprising a pair of bag opening fingers, supporting means for said fingers including bars mounted for horizontal reciprocating movement and

- which rotatably support the fingers permitting rotation thereof on a vertical axis, a member carrying said bars and mounted for vertical reciprocating movement, means vertically reciprocating said member and other means having actuation when said member is located at the extremities of its stroke to cause horizontal reciprocating movement of said bars, whereby the bag opening fingers have vertical movement in spaced planes and horizontal movement in spaced planes, and means operatively connecting the fingers with said member and constructed and arranged to produce rotation thereof as a result of their bodily movement in the horizontal planes.
15. Mechanism for opening collapsed bags comprising a frame having a vertical guide member extending the length thereof, a member mounted for reciprocating movement on said guide member, a pair of bars mounted on the respective sides of said member and adapted to have horizontal reciprocating movement with respect thereto, means connecting said bars to cause horizontal reciprocating movement thereof while permitting vertical movement of their carrying
- 20
- 25

member, means carried at the projecting end of each bar for journaling the shaft permitting rotation thereof on a vertical axis, and a bag opening finger fixed to the depending end of each shaft.

18. Mechanism for opening collapsed bags, comprising a frame having a vertical guide member extending the length thereof, a member mounted for reciprocating movement on said guide member, a pair of bars mounted on the respective sides of said member and adapted to have horizontal reciprocating movement with respect thereto; means connecting said bars to cause horizontal reciprocating movement thereof while permitting vertical movement of their carrying member, means carried at the projecting end of each bar for journaling the shaft permitting rotation thereof on a vertical axis, a bag opening finger fixed to the depending end of each shaft, links operatively connecting each shaft with said member, said links being constructed and arranged to produce rotation of the finger as a result of the horizontal reciprocating movement of its respective bar.

GEORGE LONG. 25
